UNITED STATES PATENT OFFICE

146,088

DESIGN FOR A SERVING STAND

Jack D. Renard, Seattle, Wash.

Application October 24, 1945, Serial No. 123,153

Term of patent 7 years

(Cl. D33—14)

To all whom it may concern:

Be it known that I, Jack D. Renard, a citizen of the United States, residing at Seattle, King County, Washington, have invented a new, original, and ornamental Design for Serving Stand, of which the following is a specification, reference being had to the accompanying drawing, forming part thereof, wherein—

Fig. 1 is a side perspective view of a serving stand showing my new design.

Fig. 2 is a top plan view thereof.

Fig. 3 is a side elevational view of the same.

Fig. 4 is a section on line 4—4 in Fig. 3.

I claim:

The ornamental design for a serving stand, as shown.

JACK D. RENARD.
